UNITED STATES PATENT OFFICE.

SYLVESTER NELSON, OF DETROIT, MICHIGAN.

AXLE-DIES.

1,129,417.

Specification of Letters Patent. Patented Feb. 23, 1915.

Application filed July 16, 1914. Serial No. 851,254.

To all whom it may concern:

Be it known that I, SYLVESTER NELSON, a citizen of the United States of America, residing at Detroit, in the county of Wayne and State of Michigan, have invented certain new and useful Improvements in Axle-Dies, of which the following is a specification, reference being had therein to the accompanying drawings.

10 This invention relates to dies for producing axles of that type used in connection with automobiles and other vehicles, the axles having spring perches and the ends bifurcated or forked to accommodate the 15 knuckles of steering wheels.

15 The primary object of my invention is to provide positive and reliable means, in a manner as hereinafter set forth, for expeditiously and economically producing axles 20 of the above type, said means including instrumentality for upsetting, forming, stamping, punching and bending the ends of an axle blank whereby it is practically ready for installation in connection with other 25 parts of a vehicle.

25 A further object of this invention is to provide strong and durable dies by which the ends of an axle blank can be upset, stamped to provide webbed heads, punched, 30 and cut to remove the webs from the head, the heads opened to provide forks, and then the forked ends shaped and finished, thereby permitting of a method of manufacture being carried into effect which insures a rapid 35 production with a minimum amount of waste.

With the above and other objects in view, the invention resides in the novel construction, combination and arrangement of parts 40 to be hereinafter specifically described and then claimed, and reference will now be had to the drawings, wherein—

Figure 1 is a perspective view of separated dies designed for producing an axle; 45 Fig. 2 is a vertical longitudinal sectional view of the dies assembled or closed and showing an upsetting tool or header in connection therewith; Fig. 3 is a cross-sectional view of the dies taken on the line 111—111 50 of Fig. 2; Fig. 4 is a perspective view of an axle blank; Fig. 5 is a plan of the dies; Fig. 6 is a side elevation of one of the dies illustrating the finishing or shaping of a fork especially designed for that purpose; 55 Fig. 7 is a plan and elevation of an end of a partially formed blank; Fig. 8 is an eleva-

tion and section of a portion of a blank illustrating the second operation on the blank.

In the drawings and for clearness in understanding my invention, the dies have been generally designated A and B and these dies for carrying out the first two steps in the formation of an axle are identical in construction. The dies are adapted to confront each other in a press or suitable machine by which the dies can be moved to and from one another or one of the dies remain stationary and the other movable relatively thereto. The dies are rectangular in elevation and the confronting faces thereof, at one end and adjacent the lower edges thereof, are provided with longitudinal grooves 1 and at the opposite end with rectangular recesses 2 in communication with 75 said grooves. Arranged in the recesses 2 and retained therein by detachable strips 3 are yieldable formers 4. These formers are in the form of slide blocks and are limited in their movements by the end walls of the 80 recesses 2. The inner ends of the formers are provided with sockets 5 longitudinally alining with bores 6 in said dies and said bores and sockets 5 accommodate coiled compression springs 7 which hold the formers 4 normally at the forward ends of said dies. The confronting sides of the formers 4 are provided with longitudinal grooves 8 alining with the grooves 1 in the rear ends 85 of the dies, and the ends of the grooves are 90 enlarged, as at 9 and 10 for a purpose that will presently appear. The forward ends 95 of the grooves are also enlarged as at 11 and the grooves 1 and 8 coöperate in supporting an axle blank 12 between the dies A and B 100 whereby the first step in the operation of producing an axle can be safely taken. An axle blank 12 is adapted to be frictionally held by the walls of the grooves 1 and 8 when the dies are closed and with one end 105 of the blank protruding from the forward ends of the dies, an upsetting tool or header 13 is brought into engagement with the end of the blank. This tool, as best shown in Figs. 1 and 2, has a recess 14 to receive the end of the blank, and as said tool is brought into action, the protruding end of the blank is upset and shaped in the enlarged ends 9 of the grooves 8 and the recess 14 of said tool. Besides the outer end of the blank 110 being shaped to form a head 15, the blank is upset at the confronting enlarged end 10

and 11 of the grooves 8 and 1 respectively, thereby providing a spring perch (see Fig. 7). As this first operation is performed, the formers 4 slide or yield and to a large extent release the dies of stresses and strains incurred when upsetting and shaping the axle blank 12. When the dies A and B are separated the yieldable formers assume normal position and assist in releasing the axle blank from the die.

The confronting sides of the dies A and B, at the rear ends thereof, are provided with stamping recesses 17 and these recesses are adapted to produce substantially hook-shaped heads when axle blanks are placed between said dies to enter the recesses. By reference to Fig. 8, it will be observed that when the head of the blank receives the second operation in connection with the recesses 17 that the hook-shaped head has a shank 18, a bill 19, tang 20 and a connecting web 21. These are formed by pressing the material of the head 15 into the confronting recesses 17 and the connecting web 21 is central and longitudinally of the end of the blank.

The third step or operation is that of removing the connecting web 21 which is accomplished by punching or cutting the web. The dies A and B have the rear ends thereof provided with hook-shaped recesses 23 and the recess of the die A has a punching member 25 that enters an opening 24 in the die B and removes the connecting web 21 without distorting the blank. With the recesses 23 formed in the confronting faces of the dies, the walls of said recesses firmly brace the blank while the connecting web thereof is removed.

The next or fourth operation consists of opening the hook-shaped end of the blank to form a fork. This is accomplished by providing the top of the die B with holders, one in the form of a block 26 and the other in the form of a pin 27. It is between the block 26 and the pin 27 that the blank is placed, as best shown in Fig. 5, the block 26 bracing the shank 18 of the hook-shaped end of the blank. The top of the die A is provided with a hook opening member 28 that is angularly disposed and adapted to engage the bill 19 of the blank hook, when the dies A and B are brought together. The hook is opened by bending the shank 18 against and beyond the block 26 and the

pin 27 co-operates with the block in preventing displacement of the blank during this operation. The blank is now ready for a finishing and shaping operation and with this end in view, the confronting faces of the dies A and B are provided with longitudinal grooves 29. The grooves 29 are enlarged, as at 30, to accommodate the spring perch 16 and the forward ends of the grooves are enlarged to provide a fork recess 31. With the blank held between the dies and the open hook in the recess 31, a finishing or shaping tool 32 enters the recess 31 and properly shapes the fork. This is shown in Fig. 6 and the operation which takes place is simply that of bending the shank and bill of the hook whereby the bill will aline with the tang and thus form a fork in which the knuckle of a wheel or steering apparatus can be pivotally mounted.

It is thought that the operation and utility of the dies will be apparent without further description, and while I have herein used the terms "forward" and "rear," I desire it to be understood that these terms are used as a matter of convenience in describing the invention and that the dies can be used in any desirable position in a press or machine employed for moving the dies and the tools associated therewith.

What I claim as my invention is:

Means for shaping the end of an axle blank, comprising dies having the confronting faces thereof provided with grooves and recesses, yieldable formers slidable in the recesses of said dies, detachable strips set in the faces of said dies for retaining said formers in said recesses, said formers having grooves longitudinally alining with the grooves of said dies, the grooves of said dies having ends thereof enlarged, a spring in each recess extending into the body of each die and retaining said formers in an extended position, and a header movable to and from said dies and co-operating with said formers in upsetting a blank in the grooves of said formers and said dies whereby said blank is provided with a head and a perch.

In testimony whereof I affix my signature in presence of two witnesses.

SYLVESTER NELSON.
